PORTABLE TYPEWRITER

Anton Demmel, Wilhelmshaven, Germany, assignor to
Olympia Werke AG, Wilhelmshaven, Germany, a corporation of Germany

Filed Nov. 23, 1959, Ser. No. 58,436

Claims priority, application Germany May 23, 1959

Term of patent 14 years

(Cl. D64—11)

Fig. 1

Fig. 2

FIG. 1 is a side perspective view of a portable typewriter showing my design; and

FIG. 2 is a perspective view of the opposite side thereof.

The essential features of the design reside in the portions shown in solid lines on the drawing, the type levers having been omitted for convenience of illustration.

I claim:

The ornamental design for a portable typewriter, as shown and described.
